SPINNING STOP MOTION

Floyd T. Noah, Greensboro, N. C.

Application August 19, 1935, Serial No. 36,922

2 Claims. (Cl. 118—5)

This invention relates to spinning machines and has special reference to a stop motion for preventing overrunning of the builder mechanism in such machines. More particularly the invention relates to improvements on my prior Patent No. 1,753,247, for Spinning stop motion, granted April 8, 1930.

The principal object of the present invention is to provide an improved stop motion for spinning machines which is actuated directly from the builder mechanism of the machine and which, when thus actuated, will effect opening of the circuit of the motor driving the spinning machine.

A second important object of this invention is to provide a stop motion of this character which is actuated upon the traverse element common to builder motions reaching the limit of its movement.

With the above and other objects in view, the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is an elevation of a portion of a spinning machine showing the builder motion and the parts of the invention associated therewith.

Figure 2 is an enlarged detail view, partly in elevation and partly in section, of a certain circuit breaker means used herewith.

Figure 3 is a wiring diagram showing the electric circuits of the invention.

Figure 4 is an enlarged detail view illustrating a bracket used in connection with the invention, and parts attached to said bracket.

In the embodiment of the invention as illustrated in the accompanying drawing there is shown a builder mechanism of ordinary type including a weight lever 10 which is oscillated by a cam 11 and has a traverse mechanism including the traverse guide 12 and the traverse slide 13 attached thereto.

Mounted on the lever 10 is an arm or bracket 14 which extends across one end of the guide 12. On the bracket 14 is pivoted an arm 15 which normally diverges from the bracket 14 and lies against or close to the end of the guide 12 so that the slide 13 will contact with the arm 15 and move it toward the bracket 14 as the slide reaches the limit of its movement. The arm 15 is preferably U-shaped in cross section so as to straddle the bracket 14. Clamped to the bracket 14 is one end 55 of a Bowden wire tube 16. A switch housing 17

is carried by the other end of the tube 16 and is fixed to any suitable object such as a part of the spinning machine. In the housing 17 is fixed a pair of spaced contacts 18 adapted to be bridged by a movable contact 19, which is attached to a vertically movable bar 21, formed of vulcanite or other non-conductor of electricity, which bar is slidably mounted in a block 23 being supported on a bracket 28a within the housing 17. Connected to the lower end of the bar 21 is a head 29, through which the Bowden wire passes, so that its end bears against the bar 21. Interposed between the head 29 and the bracket 28a, and surrounding the bar 21, is a coil spring 21 which tends to hold the contact 19 in engagement with the contacts 18, and to urge the Bowden wire 20 outwardly of the casing 17. The outer end of the Bowden wire is pivoted to the arm 15, as at 15a. As a result of this arrangement the upper end of the arm 15 is normally held away from the arm 20 14.

The contacts 18 are connected in a circuit 22 including the winding of an electro-magnetically operated switch 24 normally held closed, when the winding 23 is energized. The switch 24 controls the circuit 25 of the driving motor 26 which operates the spinning machine.

While the present drawing shows a particular form of builder motion it is to be understood that the device may be used with any form of builder motion having a moving part which is fed gradually in one direction as the bobbins build up, such part being termed in general a gradually fed traverse member.

With this construction it will be plain that as the slide 13 reaches the end of the traversing movement it will contact with the arm 15 and effect pushing of the wire 20 and consequent breaking of the circuit 22. Breaking this circuit will deenergize the winding 23 and allow the switch 24 to open thus breaking the circuit 25 through the motor 26 which will stop.

There has thus been provided a simple and efficient device of the kind described and for the purpose specified.

What is claimed is:

1. In a motor driven machine having a motor circuit normally closed by a magnetically closed switch, the combination of a builder motion having a gradually fed traverse member; of an electric circuit controlling said switch and including a normally closed circuit breaker, a bracket fixed to the builder motion, an arm pivoted at one end to the bracket and lying in the path of said member, and an operative connection between said

arm and circuit breaker to open the latter as the arm is moved by said member.

2. In a motor driven machine having a motor circuit normally closed by a magnetically closed switch, the combination of a builder motion having a gradually fed traverse member; of an electric circuit controlling said switch and including a normally closed circuit breaker, a bracket fixed to the builder motion, an arm pivoted at one end

to the bracket and lying in the path of said member, said circuit breaker including a pair of fixed contacts and a movable bridging contact, a casing enclosing said circuit breaker, a Bowden wire tube fixed to said bracket and casing, and a Bowden wire extending through said tube and having one end fixed to the bridging contact and its other end arranged to be moved by said arm.

FLOYD T. NOAH.
